UNITED STATES PATENT OFFICE.

WILLIAM FRIEDBERG, OF NEW YORK, N. Y.

ALARM DEVICE.

SPECIFICATION forming part of Letters Patent No. 755,125, dated March 22, 1904.

Application filed November 11, 1903. Serial No. 180,648. (No model.)

To all whom it may concern:

Be it known that I, WILLIAM FRIEDBERG, a citizen of the United States, residing at New York, in the county of New York and State of New York, have invented certain new and useful Improvements in Alarm Devices, of which the following is a specification, such as will enable those skilled in the art to which it appertains to make and use the same.

10 The object of this invention is to provide an improved house-alarm of the class known as "burglar-alarms," a further object being to provide a device of this class which is operated by placing the hand on the outer door-knob; 15 and with these and other objects in view the invention consists in a device of the class specified constructed as hereinafter described and claimed.

The invention is fully disclosed in the following specification, of which the accompanying drawing forms a part, said drawing being a sectional view of a part of a door provided with my improvement, part of the improvement being also in section, the separate parts 25 of the device being also designated by suitable reference characters.

In the drawing forming part of this specification I have shown at *a* a part of a door having a lock-space *b* and through which is passed 30 the usual knob-spindle *c*, provided with an inner knob *d* and an outer knob *d*². The spindle *c* is hollow and is provided on the inner side of the door *a* and in one side thereof with a hole *e*, through which is passed electric wires 35 *f* and *g*.

The outer knob *d*² is composed of an inner part *h* and an outer part *i*, and these parts are respectively provided with rims *h*² and *i*², the rim *i*² of the part *i* overlapping the rim *h*² of the part *h*. The rim *h*² is screw-threaded for a short distance on the outer side thereof, as shown at *h*³, while the rim *i*² is similarly threaded on the inner side thereof, as shown at *i*³, and by means of this construction the 45 part *i* is connected with the part *h* by being screwed thereonto, and after the screws *h*³ and *i*³ are disconnected the part *i* will have a short sliding movement on the part *h*, and this movement is limited by screws *j*, passed

through the slots *k* in the rim *i*² of the part *i* 50 and into the part *h*.

The wires *f* and *g* are passed into the outer knob *d*², as clearly shown in Fig. 1, and one of said wires is connected with a contact device *m* and the other with a spring-arm *n*, 55 which is bowed outwardly, as shown at *n*², and provided with an end piece *n*³, adapted to make connection with the contact device *m*, and the outer part *i* of the knob *d*² is provided centrally with an inwardly-directed projection *o*, 60 adapted to bear on the spring-arm *n* and to normally hold the part *i* of said knob in its outermost position.

At any suitable or desirable point within the house is placed an electric-alarm device *p* 65 and a battery *p*², and one of the wires *f* and *g* is connected with said alarm device and the other with the battery *p*², and another wire *p*³ also connects the alarm device and said battery, and with this construction it will be seen 70 that the alarm device *p* is placed in an open circuit, which is adapted to be closed by simply placing the hand on the outer part *i* of the knob *d*², any appreciable pressure on said part *i* being sufficient to force it inwardly, so 75 that the contact device *m* and *n*², the latter of which is on the spring-arm *n*, will be forced into connection, and when the pressure on the part *i* of the knob *d*² is removed the said part *i* will be forced outwardly and the circuit broken. 80

This device is exceedingly simple in construction and comparatively inexpensive and well adapted to accomplish the result for which it is intended, and my invention is not 85 limited to the exact details herein shown and described for making the outer part of the knob *d*² movable on the inner part thereof, and I reserve the right to make all such alterations in the construction herein shown and 90 described as fully come within the scope of my invention.

Having fully described my invention, what I claim as new, and desire to secure by Letters Patent, is—

95

1. In an apparatus of the class described, a hollow spindle for door-knobs provided at one end with a knob composed of an inner and an

- outer part, the outer part being provided with a rim which incloses a corresponding rim formed on the inner part, said outer part being also movable on the inner part longitudinally of the spindle, and two contact devices placed within said knob and normally separated and adapted to be brought together by pressure on the outer part of the knob, substantially as shown and described.
- 10 2. In an apparatus of the class described, a hollow spindle for door-knobs provided at one end with a knob composed of an inner and an outer part, the outer part being provided with a rim which incloses a corresponding rim formed on the inner part, said outer part being also movable on the inner part longitudi-

nally of the spindle, and two contact devices placed within said knob and normally separated and adapted to be brought together by pressure on the outer part of the knob, said hollow spindle being also provided with electric wires which pass therethrough and into said knob, substantially as shown and described. 20

In testimony that I claim the foregoing as my invention I have signed my name, in presence of the subscribing witnesses, this 10th day of November, 1903. 25

WILLIAM FRIEDBERG.
